(57) **CLAIM**

The ornamental design for a display screen with animated graphical user interface for vehicles, as shown and described.

DESCRIPTION

- 1.1 : is a front image;
- 1.2 : is a second image thereof;
- 1.3 : is a third image thereof;
- 1.4 : is a fourth image thereof;
- 1.5 : is a perspective view thereof;
- 1.6 : is a top view thereof; and
- 1.7 : is a right view thereof.

In 1.5 through 1.7, the outermost broken line perimeter illustrates a portion of the display screen and forms no part of the claimed design. In 1.1 through 1.5 the perimeters of the display screen and animated graphical user interface are understood to be flush.
